UNITED STATES PATENT OFFICE

2,526,113

BOTTLE CRATE

Sanford J. Blackwell, St. Louis, Mo.

Application September 30, 1947, Serial No. 777,011

3 Claims. (Cl. 220—21)

1

This invention relates to bottle crates or carriers.

An object of this invention is to provide a bottle crate which includes a metal frame formed out of extruded or shaped flat channel metal and extruded double channelled corners, the frame being cut out on the inner walls thereof for receiving the ends of the partitions or dividers so that the partitions will be locked in the frame.

Another object of this invention is to provide a bottle crate which can be easily and quickly assembled.

A further object of this invention is to provide a bottle crate wherein the dividers or partitions may be formed out of rubber, plastic or other composition material which may be reinforced by embedded rods or wires.

A further object of this invention is to provide a bottle crate which includes in one form thereof yieldable bottle locking disks for yieldably locking the bottles in the crate so that the crate can be tilted to a sharp angle without spilling out any of the bottles in the crate.

A further object of this invention is to provide a bottle crate having a metal frame formed of confronting pairs of channel members in the sides and ends thereof, the inner channel members being cut out to receive the ends of the divider cage, and formed with openings adjacent the bottom thereof to receive the ends of the bottom slats which are locked by means of cross rods or wires and the ends of the slats are engaged in openings formed in the ends of the frame.

A further object of this invention is to provide an improved bottle crate which includes a pair of handles or bails and means for removably mounting the bails on the frame.

A further object of this invention is to provide a bottle crate which includes identifying means pressed or embossed in the outer sides of the frame so that the crate can be easily and quickly identified.

A further object of this invention is to provide a crate which can be easily stacked and will withstand hard usage.

To the foregoing objects, and others which may hereinafter more fully appear, the invention consists of the novel construction, combination and arrangement of parts, as will be more specifically referred to and illustrated in the accompanying drawings, but it is to be understood that changes, variations, and modifications may be resorted to which fall within the scope of the invention as claimed.

2

In the drawings:

Figure 1 is a perspective view of a bottle crate or carrier constructed according to an embodiment of this invention.

Figure 2 is a sectional view taken on the line 2—2 of Figure 1.

Figure 3 is a sectional view taken on the line 3—3 of Figure 2.

Figure 4 is a fragmentary sectional view taken on the line 4—4 of Figure 1.

Figure 5 is a fragmentary sectional view taken on the line 5—5 of Figure 2.

Figure 6 is a fragmentary bottom plan of the device.

Figure 7 is a fragmentary sectional view taken on the line 7—7 of Figure 3.

Figure 8 is a fragmentary sectional view of one of the corners of this device on an enlarged scale.

Figure 9 is a fragmentary plan view, partly in section, of a modified form of divider or partition cage.

Figure 10 is a fragmentary sectional view taken on the line 10—10 of Figure 9.

Figure 11 is a fragmentary plan view, partly in section, of another form of divider cage construction.

Figure 12 is a fragmentary plan view, partly in section, of the divider or cage member showing the mounting of bottle retaining members thereon.

Figure 13 is a fragmentary vertical section taken on the line 13—13 of Figure 12.

Figure 14 is a plan view of one of the rubber retaining members.

Figure 15 discloses a modification of the handle structure.

Referring to the drawings, the numerals 20 and 21 designate generally a pair of side members and the numerals 22 and 23 designate generally a pair of end members forming a frame or carrier body. The side members 20 and 21 are of like construction and each includes inner and outer elongated flat plates 24 and 25. The inner plate 24 is formed on its longitudinal edges with an upper outwardly extending flange 26 terminating in a downwardly extending flange 27. The inner plate 24 also includes a lower outwardly extending flange 28 which terminates in an upwardly extending flange 29. The outer plate 25 includes an upper inwardly extending flange 30 terminating in a downwardly extending flange 31 which is disposed in face abutting relation to the upper flange 27 of the inner plate so as to thereby hold the inner and outer plates in spaced apart relation.

The outer plate 25 also includes a lower in-

wardly extending flange 32 having extending upwardly from the inner end thereof a vertical flange 29 and coacts with the upper flanges 27 and 31 in holding the inner and outer plates in spaced parallel relation. The outer plate 25 is formed between the ends thereof with an inwardly offset wall 34 on which a label or identifying member 35 is adapted to be secured. The plate or outer wall 25 is also formed with a pair of depressed outer portions 36 and an outwardly offset member 37 extends outwardly from the depressed wall or portion 36. The offset portion 37 is constructed in the configuration of a bottle which is of a design similar to the character or kind of bottles which are to be used with this crate or carrier so that the distributor or owner of the carrier will know from a glance at the offset design 37 the kind of bottles which are to be placed in the crate or carrier.

The end members 22 and 23 are also of like construction and each includes an inner plate 38 and an outer plate 39. The inner plate 38 is formed on its upper lengthwise edge with an outwardly extending flange 40 and a depending flange 41 extends from the outer edge of the flange 40. The plate 38 also includes a lower outwardly extending flange 42 and an upwardly extending flange 43 extends from the outer edge of the flange 42. The outer plate or wall 39 includes an upper inwardly projecting flange 44 terminating in a depending flange 45 abutting against the upper flange 41. The outer wall or plate 39 also includes a lower inwardly projecting flange 46 and an upwardly extending flange 47 abutting against the flange 43.

A hand hole or opening 48 is formed in the two plates 38 and 39 between the ends thereof and between the upper and lower edges. The hand hole 48 is defined by flanges 49 and 50 extending outwardly from the horizontal edges of the hole or opening 48 and the flange 49 has extending upwardly therefrom an upper flange 51 whereas the lower horizontal flange 50 has depending therefrom a flange 52. The opening 48 is also defined by vertical confronting L-shaped flanges 53 and 54 so that when the two plates 38 and 39 are secured together as will be hereinafter described the space between the plates 38 and 39 will be closed by the flanges formed on these plates about the opening or hole 48.

The respective side and end members are adapted to be secured together by means of connecting corner members generally designated as 55. The corner members 55 include a U-shaped coupling member 56 between the parallel sides of which the adjacent ends of the side members are adapted to engage. The corner members 55 also include an L-shaped member 57 formed integral with the U-shaped member 56 and extending at right angles with respect to the U-shaped member 56 so as to thereby provide right-angularly disposed channel 58 within which the adjacent end of an end member is adapted to engage.

The end of a side member is adapted to be secured in the U-shaped channel member 56 by means of rivets or fastening members 59 which extend transversely across the parallel sides of the U-shaped member 56. The end members 22 and 23 are secured in the channel 58 by means of elongated bars or rods 60 which extend through the outer side of the L-shaped member 57 and project between the plates 24 and 25 forming the side members. The ends of the rod or bar 60 are upset as indicated at 61 so that the end members will be firmly secured within the

channels 58, but when it is desired to repair either a side or end member, the rivets and securing bar 60 may be removed and new side or end members inserted in the respective channels. These channel members 55 are adapted to be formed from extruded material.

A bottom wall generally designated as 62 is disposed within the frame formed of the opposite sides and opposite end members and the bottom wall is preferably constructed of lengthwise extending slats or narrow strips 63 which are formed with reduced opposite ends 64 extended through holes 65 formed in the inner walls 38 of the end members.

Preferably transversely extending connecting bars 66 extend horizontally and transversely through the slats or strips 63 and are adapted to be extended through openings 67 formed in the lower portions of the side walls or plates 24. 20 The bottom forming slats 63 are preferably disposed in spaced apart relation as clearly shown in Figure 3, so as to provide relatively open bottom for the crate.

A divider or partition forming cage generally 25 designated as 68 is disposed within the frame or body formed by the opposite sides and ends. The divider or cage construction includes a plurality of lengthwise extending parallel flat strips 69 with which transversely extending parallel strips 70 are interjoined. The transverse strips 70 extend from the upper edge of the frame to the bottom wall 62 whereas the longitudinal divider strips 69 terminate at the lower edge, as 30 shown in Figure 2, above the bottom wall 62. 35 The transverse strips 70 are formed with outwardly opening slots 71 within which the reduced connecting portion 72 of a longitudinal strip is adapted to engage. The inner side walls 24 of the side members are formed with vertically elongated openings 73 within which opposite end tongues 74 carried by the transverse strips 70 are adapted to snugly engage. The longitudinal strips 69 project at their opposite ends through openings 75 formed in the inner 40 walls 38 of the end members, the longitudinal strips 69 having tongues 76 at the opposite ends for engagement in the openings 75.

As shown in Figure 2, the middle longitudinal strip 69a is cut off at the opposite ends thereof 50 as indicated at 77 on an upward and outward inclination so that the outer ends of the middle divider strip 69a will not interfere with the projection of a hand through the hand holes 48.

The partition forming member or cage 68 is 55 formed with arcuate vertically extending cut-outs 78 and 80 in the longitudinal and transverse partition members respectively so that these partition members may be disposed in a manner to provide relatively small pockets with the bodies of the bottles engaging in the vertical arcuate cut-outs or channels 79 and 80.

A pair of carrying handles or bails 81 are 60 adapted to be removably connected with the crate and each handle or bail includes a U-shaped upwardly and inwardly inclined member 82 having the bight 83 thereof uppermost and comprising the grip. The parallel sides 84 of the U-shaped members 82 extend to the opposite 65 end members 22 and 23 and vertical extensions 85 extend downwardly from the outer ends of the parallel legs 84 terminating in inwardly and upwardly inclined bars 86. The inner ends of the bars 86 have formed integral therewith hooks 75 87 which are adapted to engage over the end

transverse connecting bars 66 as clearly shown in Figures 2 and 7.

The outer walls 39 of the opposite end members are formed with elongated openings or slots 88 so that, if desired, the carrying handles or bails 81 may be formed with hooks in the vertical portions 85 thereof to engage in the slots 88.

Referring now to Figures 9 and 10, there is disclosed modified form of cage or partition construction wherein the longitudinal strips 89 are formed integral with the transverse strips 90. The strips 89 and 90 are preferably formed out of composition material such as plastic or the like and the longitudinal strips 89 are adapted to be reinforced by embedded reinforcing rods 91. The transverse strips 90 are adapted to be reinforced by embedded reinforcing strips or rods 92.

Referring now to Figure 11, there is disclosed another form of divider or cage construction wherein the longitudinal strips 93 are formed integral with the transverse strips 94 and these longitudinal and transverse strips are formed out of rubber or other inherently yieldable material. The longitudinal strips 93 are reinforced by embedded reinforcing rods 95 and the transverse strips 94 are reinforced by embedded reinforcing rods or bars 96.

Referring now to Figures 12, 13 and 14, there is disclosed a yieldable bottle locking or holding disk 97 which is adapted to be combined with the cage construction shown at 68 or with the cage constructions shown in Figures 9 and 11. The disk 97 is formed as shown in Figure 14 with oppositely extending slots 98 within which the transverse partition members 70 are adapted to engage. The disk 97 is formed with a narrow connecting part 99 between the two slots or openings 98 which engages on the lower end of the vertical slot 71 which is formed in the transverse partition members 70. The bottle locking or holding disks 97 are designed particularly for the use where bottles are formed with reduced portions in the body thereof adjacent the lower ends, and where these locking or holding disks are used, the bottles may be inserted in the respective compartments between dividers and are bent sufficiently to permit the bottom of the bottle to pass the disks and will then assume their normal positions which will be within the reduced body portions of the bottle. These disks are particularly desirable where the crate or carrier is carried by only one end which has a tendency to dispose the bottles in the crate in substantially horizontal position where they might readily fall out.

Referring now to Figure 15, there is disclosed a modification of the handle structure. An elongated cord 100 which is of a length sufficient to be looped as shown by the wire handle 82 is provided at the opposite ends thereof with spring clasps 101 which are adapted to engage the cross bars 66 and the looped cord then extended outwardly from beneath the frame, upwardly along the ends of the frame, and then extended inwardly.

With respect to the extruded channeled corners herein disclosed, it will be understood that these corners may if desired be formed from rubber or the like.

I claim:

1. A bottle crate comprising a rectangular frame formed of opposite side and end members, 75

each of said members including inner and outer plates, confronting flanges carried by the upper and lower edges of said plates for holding said plates in spaced relation, channelled corner members fixed to the opposite ends of said side members, each corner member being formed of a pair of right-angularly disposed channels, a rod extending through both end members, each side member and said corner members for securing said crate together, bottom forming means in said frame, and a compartment forming cage in said frame.

2. A bottle crate comprising a rectangular frame formed of separate opposite side and end members, each member including spaced inner and outer plates, outwardly extending upper and lower flanges carried by said inner plates, right-angularly disposed flanges carried by said upper and lower flanges, said outer plate including inwardly projecting upper and lower flanges and right-angular flanges carried by the latter disposed in abutting relation with respect to said first named right-angular flanges, a corner member for the adjacent ends of said side and end members, each corner member being formed of a pair of right-angularly disposed channels, means fixing said end members in said channels, and rods extending between said end members, through said side members and said corner members, securing said crate together.

3. In a bottle crate, a divider cage formed of parallel longitudinal strips and parallel transverse strips, certain ones of said strips having slots at the crossing points within which the intersecting ones of said strips engage, and a yieldable bottle retaining disk at the crossing points of said strips and disposed in said slots below the upper edges of said strips whereby to yieldably hold bottles within the compartments formed by said strips.

SANFORD J. BLACKWELL.
